DESIGN FOR A TEXTILE FABRIC

Albert J. Bartson, Ridgewood, N. J.

Application September 1, 1936, Serial No. 64,670

Term of patent 3½ years

To all whom it may concern:

Be it known that I, Albert J. Bartson, a citizen of the United States of America, residing in the village of Ridgewood, in the county of Bergen and State of New Jersey, have invented a new, original, and ornamental Design for a Textile Fabric, of which the following is a specification, reference being had to the accompanying drawing, forming part thereof, wherein

I claim:

The ornamental design for a textile fabric, substantially as shown.

ALBERT J. BARTSON.
